UNITED STATES PATENT OFFICE.

CLAYTON F. WETMORE, OF JERSEY CITY, NEW JERSEY, ASSIGNOR TO
NATIONAL CASKET CO., OF NEW YORK, N. Y., A CORPORATION OF
NEW YORK.

DESIGN FOR A CASKET, COFFIN, OR SIMILAR ARTICLE.

No. 38,059.

Specification for Design.

Patented June 5, 1906.

Application filed March 27, 1906. Serial No. 308,372. Term of patent 14 years.

To all whom it may concern:

Be it known that I, CLAYTON F. WETMORE, a citizen of the United States, residing at Jersey City, in the county of Hudson and State of New Jersey, have invented a new, original, and ornamental Design for Caskets, Coffins, or Similar Articles, of which the following is a specification, reference being had to the accompanying drawing, forming a part thereof.

The figure is a side elevation of a casket, showing my design.

I claim—

The ornamental design for a casket, coffin or similar article as shown.

CLAYTON F. WETMORE.
